[57] CLAIM

The ornamental design for a beverage can, as shown and described.

DESCRIPTION

FIG. 1 is a perspective view of the beverage can.

FIG. 2 is a top view of the beverage can.

FIG. 3 is a side elevational view of the beverage can opposite the frangible area on the lid which opens into the drinking aperture; and,

FIG. 4 is a side elevational view of the beverage can rotated 90 degrees from that shown in FIG. 3, it being understood that the opposite is a mirror image thereof.
